UNITED STATES PATENT OFFICE

167,156

LENS CUTTING MACHINE

James F. McCarthy, Oaks Corners, N. Y., assignor
to Shuron Optical Company, Inc., Geneva, N. Y.,
a corporation of New York

Application September 5, 1951, Serial No. 16,517

Term of patent 14 years

(Cl. D37—1)

To all whom it may concern:

It is known that I, James F. McCarthy, a citizen of the United States of America, and a resident of the village of Oaks Corners, in the county of Ontario and State of New York, have invented a new, original, and ornamental Design for a Lens Cutting Machine, of which the following is a specification, reference being had to the accompanying drawings, forming part thereof:

In the drawings:

Figure 1 is a perspective view of the front and right-hand side of a lens cutting machine, showing my new design; and

Figure 2 is a perspective view of the rear and left-hand side thereof.

I claim:

The ornamental design for a lens cutting machine, substantially as shown.

JAMES F. McCARTHY.
